NON-BOIL OVER MILK PAN

Bernard Sams, London, and Albert Edward Cook, Wolverhampton, England, assignors to Tower Housewares Limited

Filed May 7, 1973, Ser. No. 358,162

Claims priority, application Great Britain Nov. 9, 1972

Term of patent 14 years

Int. Cl. D7—02

U.S. Cl. D7—95

FIG. 1.

FIG. 2.

FIG. 3.

FIG. 4.

FIG. 1 is a top plan view of a non-boil over milk pan, showing our new design.

FIG. 2 is a side elevation thereof;

FIG. 3 is a top rear perspective view thereof; and

FIG. 4 is a bottom rear perspective view thereof.

We claim:

The ornamental design for a non-boil over milk pan, substantially as shown.
